(57) **CLAIM**

The ornamental design for a retainer of a container for storing and shipping wafers as shown and described.

DESCRIPTION

FIG. 1 is a front perspective view showing the use state of a retainer of a container for storing and shipping wafers of the present invention, illustrated with a container for storing and shipping wafers;

FIG. 2 is a front view of the retainer of a container for storing and shipping wafers of the present invention;

FIG. 3 is a rear view thereof;

FIG. 4 is a top plan view thereof;

FIG. 5 is a bottom view thereof;

FIG. 6 is a right side view thereof;

FIG. 7 is a left side view thereof;

FIG. 8 is a front perspective view thereof;

FIG. 9 is a rear perspective view of thereof;

FIG. 10 is an enlarged front view thereof, taken along the lines 10-10 of FIG. 2;

FIG. 11 is an enlarged rear view thereof, taken along the lines 11-11 of FIG. 3;

FIG. 12 is an enlarged top plan view thereof;

FIG. 13 is an enlarged right side view thereof, taken along the lines 13-13 of FIG. 6;

FIG. 14 is an enlarged front perspective view thereof, taken along the lines 14-14 of FIG. 8; and,

FIG. 15 is an enlarged rear perspective view thereof, taken along the lines 15-15 of FIG. 9.

The features shown in broken lines depict environmental subject matter only and form no part of the claimed design. The oblique shade lines in the figures show a transparent or translucent material.

The portions that would be visible behind the transparent or translucent surface of the claimed portions are omitted for a clear disclosure of the surface configuration.
